UNITED STATES PATENT OFFICE.

HASTINGS H. JOHNSON, OF MINNEAPOLIS, MINNESOTA.

WIRE-MEASURING DEVICE.

Application filed April 28, 1924. Serial No. 709,444.

My invention provides an extremely simple and highly efficient lineal measuring device especially adapted for the measuring of wire, etc., and, generally stated, the invention consists of the novel devices and combinations of devices hereinafter described and defined in the claims.

Wire, as is well known, is commonly carried in stock wound in large coils and is sold by the pound. However, a customer seldom orders wire by the pound but will order some certain number of feet of wire of a specified size. In the use of the wire measuring device, the desired length of wire is unwound from the supply coil and onto a drum, is then cut off and weighed, and the cost thereof calculated by weight, but this operation insures the proper length of wire.

The commercial form of my wire measuring device is illustrated in the accompanying drawings, wherein like characters indicate like parts throughout the several views.

Referring to the drawings:

Fig. 1 is a side elevation showing the wire measuring device, some parts being broken away;

Fig. 2 is an enlarged section taken on the line 2—2 of Fig. 1, some parts being broken away;

Fig. 3 is a plan view of the measuring device shown in Fig. 1;

Fig. 4 is a plan view of the wire measuring device proper;

Fig. 5 is a front elevation of the parts shown in Fig. 4;

Fig. 6 is a section taken on the line 6—6 of Fig. 4; and Fig. 7 is a fragmentary section taken on the line 7—7 of Fig. 1.

The movable parts of the device are mounted on a framework, which, as shown, is of rectangular form, being made up of horizontal upper and lower pipes 7 and end posts 8 rigidly connected at the upper corners of the frame by elbow couplings 9 and rigidly connected at the lower corners of the frame by couplings 10 provided with supporting feet 11. Secured to and rising from a lateral projection from one of the couplings 9 is a spindle 12 on which the wire-coil-containing reel 13 is rotatably mounted. This reel 13, as preferably designed, comprises a base ring 13' connected by radial arms 14 to the lower end of the long sleeve-like hub 15 that is detachably and rotatably mounted on the spindle 12. The reel 13 is arranged to be put under slight frictional resistance to rotation by

a coiled spring 16 compressed between a washer 17 and a flanged tension-adjusting nut 18, which latter has threaded engagement with the upper end of the spindle 12. To the arms 14 of the reel 13 are pivotally connected curved centering arms 19 adapted to be turned radially outward to engage and hold coils of wire of different internal diameter and to hold the same centered in respect to the axis of the reel 13. These arms 19 are preferably made up of flat metal strips bifurcated at their lower ends to straddle and frictionally engage the respective radial arms 14 to which they are pivotally connected by rivets or bolts 19^a.

The wire unwound from the supply reel 13 is adapted to be wound upon a receiving reel 20 arranged to rotate on a horizontal axis and journaled to the other upper corner of the frame. This reel 20 may be of any suitable form, so far as my present invention is concerned, but, as shown, it comprises a tapered drum 20' provided with a relatively fixed side 21 and a detachable side 22, which side members, as shown, are formed by cross bars. This reel 20 is rotatably and detachably journaled on a horizontal spindle 23 that projects from the upper front corner coupling 9. As will now be noted, the two reels 13 and 20 are so supported that wire unwound from the supply reel 13 will go to the receiving reel 20 on what will closely approximate a straight line that is substantially parallel to the upper frame bar 7, but, of course, this line of travel of the wire will vary as the supply coil is unwound and diminished in size. In Figs. 1 and 3, the coil of wire on the supply reel 13 is indicated by the character A, the coil wound onto the receiving reel is indicated by the character B, and the wire on its way from the coil A to the coil B is indicated by the character C.

Aside from certain relative arrangement of the different elements, the chief novelty of this case resides in the wire-measuring device proper, which is supported from the intermediate upper portion of the frame between the two reels 13 and 20 and which measuring device, as at present commercially made and sold, comprises as follows: The numeral 24 indicates a bracket that is rigidly secured on the intermediate portion of the upper frame bar 7, as shown, by means of set screws 25 that make the same adjustable. The upper portion of the bracket 24 is in the form of a horizontal shelf 24' to which

a horizontal face plate 26 is secured. This face plate 26, at its rear edge, is provided with an upstanding back flange 26^a having a horizontal rearwardly projecting flange 26^b to which the reduced threaded lower ends of a pair of parallel guide posts 27 are rigidly secured by nuts 27^a.

The numeral 28 indicates a drum-like measuring wheel secured to a shaft 29 journaled in bossed openings 29^a in the sides of a yoke-like rectangular cross head 30. This cross head 30, at its rear side, has projecting upper and lower guide lugs 30^a that slide freely in a vertical direction upon the guide posts 27. The shaft 29, at its rear end, is connected to the unit member of a register or tally of the well known cyclometer type, wherein the unit wheel carries the tens to wheels of higher order on the decimal plan. The casing of this register is indicated by the numeral 31 and the unit wheel is indicated by the numeral 32. The casing 31 is supported by a shelf 33 (Fig. 6) projected from the back of the cross head 30 frame 30. The construction of this register need not be further considered, for the reason that such devices may be purchased on the market and the construction and operation thereof are well known. It should be stated, however, that the circumference of the measuring wheel 28 is exactly one foot, so that the register will record the length of wire in feet. To indicate inches, the shaft 29 may be provided with a small wheel 34 located outside of the casing 31, where it may be readily seen. This wheel 34 should be peripherally marked to indicate inches. The register may be provided with the customary means for quickly resetting to zero. The knob 35 shown in Fig. 6 is a part of such resetting device.

The measuring wheel 28 is arranged to work directly over the face plate 26 and to run close to the flange 26^a. The wire C will be guided on the face plate and the wheel 28 will be gravity-held in contact therewith so that it will be driven by the wire C when the latter is drawn over the face plate. For guiding the wire C in proper contact with the measuring wheel 28, I preferably provide both vertically and laterally adjustable gauge devices arranged to engage the wire C on both sides of the measuring wheel 28. The vertically adjustable gauge devices are in the form of horizontally projected studs 36, the reduced threaded ends of which work with freedom for vertical adjustments in vertical slots 37, (see Figs. 2 and 5), formed in the back flange 26^a of the face plate 26; and the said threaded ends are provided with nuts 38, which, when tightened, securely hold said studs in set positions for best action on the wire C of any particular size. The horizontally adjustable gauge device is in the form of a gauge

plate 39 rigidly but adjustably secured to the face plate 26 by clamping bolts 40 having thumb nuts 40^a and which bolts work through slots 40^b in the gauge plate 39 and closely fit bolt holes 40^c in said face plate 26 and in the shelf 24^a. The gauge plate 39, at its inner edge, has an upstanding gauge flange 41. The flange 41 and the gauge plate 39 are cut away to clear the lower portion of the measuring wheel 28 and to permit the latter to frictionally press the smallest wire or even to rest freely upon the face plate 26. This gauge plate 39 and the back flange 26^a of the face plate 26 prevent the wire C from moving laterally out from under the measuring wheel 28.

This device will very frequently be used to measure lamp cord or similar fabric-covered wire. The measuring wheel 28, when used to measure rough or ordinary insulated wire, will become soiled or may accumulate more or less tar or dirt and, hence, when the device is used to measure lamp cord or silk-covered wire, I provide simple means for preventing the same from becoming soiled, by causing it to run in contact with a different face surface of the measuring wheel.

The means shown for the above purpose is a pair of small metal guide clips 42 having perforated ends clamped between the shoulders of the gauge pins 36 and the back flange 26^a and provided with coiled or cylindrically bent free ends. When the coiled ends of the clips 42 are turned downward, as shown in Figs. 4, 5 and 6, the wire or cord C will be caused to travel close to the gauge flange 41 but far from the back flange 26^a and, hence, to come into contact with a face surface of the measuring wheel 28 that has not been soiled by contact with ordinary or rough wire. When the ordinary wire is to be measured, the gauge clips 42 may be turned upward and there held when the nuts 38 are tightened; and then, the gauge plate 39 should be adjusted closer toward the back flange 26^a so that the wire will be caused to contact with the face surface of the measuring wheel 28 that is quite close to the said back flange 26^a, (see Fig. 3).

The numeral 43 indicates a thin spring metal scraper blade that is anchored by screws or other suitable means to the frame 30, overlies the peripheral surface of the measuring wheel 28 and is adapted by pressure of the finger to be forced into contact therewith and thereby caused to scrape and clean the measuring wheel when the latter is rotated.

This measuring device has been put into actual use and has been found highly efficient for the purposes had in view. It is of simple construction, has no parts that are likely to get out of order, and, moreover, is a self-contained structure, all of the parts

- of which are on a common frame and capable of being readily moved about or transported as an entirety. It has been found not only to be a great labor saver both in the measuring and in the handling of wire, but to be very accurate in its measurements. The measuring wheel, under the force of considerable weight, is caused to float upon and ride in frictional contact with the wire.
- 10 The wire is caused to take a straight line of travel in a horizontal plane that is tangential to the peripheral surface of the measuring wheel and in a vertical plane that intersects the axis of rotation of the measuring wheel at ninety degrees.

The wire should be cut off at and measured from a point that is on the right-hand or delivery side of the measuring device proper, so that the measuring device will be left "threaded" with wire after each cutting operation. However, the wire can be very easily threaded through the measuring device whenever that becomes necessary. A coil of wire can be quickly and easily thrown onto the receiving reel and that portion of the wire that has been measured, wound upon the receiving reel, and cut off from the main wire, may be easily removed laterally from the receiving reel when the removable side of the latter has been displaced. No one of the several elements of the complete lineal measuring device can become accidentally separated from the other and, therefore, always remain in proper cooperative association.

The lineal measuring device above described has been referred to chiefly as a device for measuring wire, but it is well adapted for use in measuring various other things, such as belting, ribbon, or other rolled or ribbon-like materials. The lineal measuring device proper, which, as shown in the drawings, is supported on the bracket 24, is capable of being readily removed from, applied to, and used upon a counter, bench, or table. The measuring wheel is adapted to be yieldingly pressed downward, either solely by the action of gravity or by the combined action of gravity and spring devices.

50 27^a. The important thing is that it is yieldingly pressed toward the material to be measured and will maintain its frictional contact therewith and will adapt itself to all irregularities or variations in thickness of the material being measured.

What is herein treated as the front of the machine is at the right in respect to Fig. 6 because that is the side at which the operator will stand.

60 What I claim is:

1. A lineal measuring device comprising a face plate having a gauge flange at its rear side, an adjustable gauge plate mounted on said face plate and spaced from the gauge flange of the latter, a vertically movable

yieldingly depressed floating frame located above said face plate, a mounting for said frame, a measuring wheel journaled to said floating frame and arranged to run in frictional contact upon a wire or the like drawn over said face plate, and a register also carried by said floating frame and driven from said measuring wheel, the said adjustable gauge plate underlying a portion of said measuring wheel and being cut away to clear the same and permit said measuring wheel to engage said face plate.

2. A lineal measuring device comprising a face plate having a fixed rear gauge flange and a horizontally adjustable front gauge flange, a vertically movable floating frame working above said face plate, a mounting for said frame, a measuring wheel journaled to said floating frame and arranged to frictionally run upon a wire or the like drawn over said face plate, and vertically adjustable gauge pins located one on each side of said measuring wheel but above said face plate.

3. A lineal measuring device comprising a face plate having a fixed rear gauge flange and a horizontally adjustable front gauge plate, a vertically movable floating frame working above said face plate, a mounting for said frame, and a measuring wheel journaled to said floating frame and arranged to frictionally run upon a wire or the like drawn over said face plate, said adjustable gauge plate being cut away to clear said measuring wheel and permit the latter to run frictionally upon the wire or the like drawn over said face plate.

4. A lineal measuring device comprising a frame, a face plate supported by said frame and having an upstanding rear gauge flange, upright guide posts secured to and projecting from said flange, wire-engaging guides supported by said face plate, a floating frame slidably mounted on said guide posts, a measuring wheel journaled to said floating frame and arranged to run in frictional contact with the wire or the like drawn over said gauge plate, and a register mounted on said floating frame and driven from said measuring wheel.

5. A lineal measuring device comprising a face plate having an upstanding fixed rear gauge flange, vertical guide posts secured to and rising from the rear flanged portion of said face plate, a floating frame mounted for vertical movements on said guide posts, a measuring wheel journaled to said floating frame and working immediately above said face plate, a register carried by said floating frame and operated by said measuring wheel, and a movable gauge plate adjustably secured on said face plate and having at its inner edge an upstanding gauge flange, said upstanding gauge flange and a portion of the body of said gauge plate being cut away

on a curved line to clear said measuring wheel and permit the same to engage said face plate.

6. The structure defined in claim 5 in further combination with gauge clips adjustably secured to the rear gauge flange of said face plate and movable to and from operative positions.

7. The combination with a supporting frame, of a supply reel mounted on said frame on a vertical axis and having a body portion on which a coil of wire is adapted to be rested with the coil in a horizontal plane,

a receiving reel mounted on said frame on a horizontal axis and adapted to support a coil in a vertical plane, a measuring device mounted on said frame between said two reels, and a friction device applied to said first noted reel, whereby when wire is wound from said first noted reel onto said second noted reel said wire will be drawn taut and hence straight as it is moved through said measuring device.

In testimony whereof I affix my signature.

HASTINGS H. JOHNSON.
